Application June 17, 1941, Serial No. 398,429

18 Claims. (Cl. 51—309)

This invention relates to abrasive tools and to methods of making the same. More specifically, the invention relates to an improved method for making solid metallic tool bodies containing abrasive grains distributed therethrough and fixed therein in an improved manner.

The invention contemplates a novel and improved method for fabricating the metallic body portion or abrasive grain bonding medium thereof, and an improved method of mounting the abrasive grains therewithin.

One object of the present invention is to provide an improved method for mounting abrasive granules within a solid metal tool body, whereby the abrasive granules are locked within the tool body in an improved manner and whereby crushing of the abrasive granules during the mounting process is avoided.

Another object of the present invention is to provide an improved abrasive tool comprising individual abrasive grains and a bonding medium for uniting the whole into an integral structure of improved strength; the abrasive grains being distributed throughout the structure in an improved manner and in accord with a predetermined plan of arrangement.

Another object of the present invention is to provide an improved abrasive wheel of increased structural strength.

Another object of the present invention is to provide an improved method of introducing the abrasive granules into the bonding medium during manufacture of an abrasive tool.

Another object of the invention is to provide an improved abrasive tool in which the abrasive ingredients thereof are distributed throughout the body of the tool in accord with any desired plan of varying concentration, and in which the abrasive granules are locked within the body of the tool in an improved manner and are unchanged from the grain size in which the abrasive granules were originally furnished.

Another object of the invention is to provide an abrasive tool wherein the abrasive granular ingredients thereof are distributed throughout the body of the tool in such manner as to expedite and make more economical the redressing of the cutting face of the tool subsequent to intermittent use thereof in an improved manner. Other objects and advantages of the invention will appear from the specification herein.

In the drawing:

Fig. 1 is a side elevation of a typical abrasive wheel of the invention;

Fig. 2 is a typical section through the wheel of Fig. 1;

Fig. 3 is a diagrammatic sectional view through a mold and press apparatus illustrating a step 5 of the fabrication method of the invention;

Fig. 4 is a fragmentary section, on an enlarged scale, through a matrix forming element having mounted thereon abrasive granules preliminary to final fabrication of a tool of the invention;

Fig. 5 is a side elevation of another form of abrasive carrying wheel of the invention;

Fig. 6 is a typical sectional view through the wheel of Fig. 5; and

Fig. 7 is a plan view, on an enlarged scale, of a 15 fragment of a fabricating element of the wheel of Figs. 5 and 6, showing the mounting of abrasive granules thereon in accord with the method of the invention.

In practicing the invention, the abrasive grits 20 to be employed are united with a novel form of bonding medium which is made up by assembling in laminated manner sheets of the bonding material. For example, as illustrated in Figs. 1-4, a wheel 10 of the invention is shown as comprising 25 a series of discs 11 which are formed of sheet metal disposed in side-by-side relation and pressed and fused together to form a unitary mass in the desired form of the abrasive wheel. The discs 11 may be either of smooth surface 30 form or they may be in the form of deformed sheets; knurled or scratched or acid-etched or otherwise treated to provide abrasive retaining pockets therein. The metal sheets 11 are preferably formed of a metallic substance which is 35 initially relatively soft and "mushy" at temperatures below the fusion point thereof, and readily weldable and adapted to receive subsequent heat treatments for tempering to desired degrees of hardness and toughness, for purposes as will be 40 explained hereinafter.

To fabricate the wheel 10, the discs 11 are 45 separately coated with abrasive kernels 12 in a predetermined manner to provide the desired relative grit concentration in any given case, and the discs are then arranged in superposed relation and subjected to a fusing temperature and then to pressure as provided for by opposed die devices 15 and 16 (illustrated diagrammatically in Fig. 3). For example, in order to provide the 50 abrasive ingredients of the wheel in concentrated form in the regions of the most active working portions of the wheel, the individual discs going into the make-up of the most active working portions of the wheel will preferably be coated 55 with increased concentrations of abrasive as com-

pared to the discs going into the make-up of the relatively inactive portions of the wheel. Thus, in connection with the manufacture of a V-shaped groove cutting wheel as illustrated in Fig. 2, the center discs 11 will be initially coated with greater quantities of abrasive kernels than are the discs at the opposite side portions thereof. The ridge-like peripheral form of the wheel may be obtained either by providing the discs 11 of appropriately different diameters whereby the building up of the laminated structure will automatically provide the approximate form desired and avoid waste of expensive abrasive grains, or by using discs of equal diameters and subsequently dressing the wheel to desired form following the fusion process. Preferably, a temporary binder to hold the abrasive grains in position upon the metal sheets prior to fusion of the latter together will be employed, and for this purpose a layer of lauryl alcohol will be smeared upon the metal sheets as indicated at 18 (Fig. 4) to engage the grains 12 against accidental displacement from their proper positions upon the sheets prior to final fusion. It has been found that lauryl alcohol has the necessary adhesive properties for causing the abrasive grains to remain in properly distributed relation during subsequent handling of the metal foil, and has the property of complete volatilization under temperatures associated with the fusion of the metal sheets and is thus completely eliminated so that ultimately no other substance remains between the abrasive granules and the fused metal.

It is contemplated that various kinds of abrasive granules may be employed in connection with the method of the invention and that the sizing of the abrasive granules will be regulated as desired and in accordance with the character of the work to be done by the finished tool. It is also contemplated that in connection with the initial deposition of the abrasive granules upon the body elements 11 any other suitable means for accomplishing the desired distribution may be employed, and that in lieu of lauryl alcohol any other suitable oily or greasy paste or liquid temporary adhesive substance may be employed, or that the abrasive grains may simply be dusted upon the strip elements without the use of any carrier substance.

In order to provide the matrix portions of the tools of the invention of preferred form, the invention contemplates usage of a special form of metallic substance which is adapted to be heat-treated in a special manner subsequent to fabrication of the tools whereby the matrix portions thereof are given improved characteristics for the purpose intended. For example, I have found that the disc elements 11 of Figs. 1-4 may, for certain tool purposes, be formed of an initially soft and temperable steel, or of a suitable member of the so-called copper base alloy group which is adapted to be heat-treated to provide in the finished product enhanced properties of toughness and resistance to wear and resistance to dislodgment of the abrasive granules embedded therein. It will of course be understood that the matrix metal of an abrasive tool may be undesirably soft and non-resistant to wear whereby the tool will be unduly deteriorated under service conditions without obtaining full benefit of the abrading capacities of the granules embedded therein. Also, it will be understood that the matrix metal may be in some cases so resistant to wear as to be non-self-dressing, whereby it will be necessary from time

to time to cut away surface portions of the tool for reexposure of abrasively active portions thereof. Also, it is most desirable that the matrix be not too ductile such as would otherwise permit the abrasive granules to be rolled out of their sockets within the matrix; nor must the matrix be too brittle whereby it would be subject to undue disintegration under service conditions and the abrasive granules would tend to dislodge therefrom prior to full utilization of the abrasion capacities thereof.

I have found that for the purpose of the invention the disc elements 11 may be desirably formed of various grades of carbon steel, or of a copper base alloy containing from a small amount up to 16% aluminum, with or without appreciable addition of other metals such as iron, nickel, and perhaps tin and zinc. For example, a specific alloy which I have found to be extremely suitable for the purpose is a commercially available alloy containing approximately 89% copper; 10% aluminum; and 1% iron. Such metal fuses at from between 1700° F. to 1900° F., depending upon the proportion of the iron content, and thus is well suited to the method of the invention in connection with the fabrication of abrasive tools employing diamond dust or the like because of non-production of deleterious effects upon the abrasive ingredients at such temperatures. I have found that subsequent to the heating and pressing fabrication method of the invention as described hereinabove, when employed in connection with the metallic alloy substances specified, the fabricated tools may be then heat-treated by heating and quenching in water at from 1500° F. to 1600° F., followed by tempering at between 1100° F. and 1200° F. Such treatment imparts to the matrix substance of the finished tool optimum strength and ductility characteristics which provide a "self dressing" tool adapted to perform most efficiently from the standpoint of utilization of the abrasion capacities of the abrasive granules disposed within the matrix. Similar suitable heat treating processes may be applied to the welded tool of the invention when fabricated of steel matrix forming elements as explained hereinabove, for providing the finished product of the desired grit retaining characteristics. Preferably, the process of welding the steel matrix elements together will be performed in a reducing atmosphere.

The fusion process is preferably carried out to such extent that all evidence of the original laminated structural form will have disappeared, and in such case a section taken in any direction through the finished product will reveal simply a homogeneous, dense, coalized metallic mass in which are interspersed the abrasive particles in accord with the predetermined plan of their relative arrangement therein.

A particular feature of the invention resides in that the metallic laminae for fabrication of the tool are selected so as to be initially relatively soft and adapted to readily soften at temperatures just below the temperature of welding so that the abrasive grains may be originally furnished of uniform desired size and will then become mounted within the body structure of the tool without having been crushed or structurally weakened during the tool assembly process. Such crushing of the abrasive granules between the adjacent metal surfaces will be avoided because of the softness of the metal and the low degree of pressure needed to be applied to bring

the metallic laminae into intimate welding position. Thus, the abrasive granules become permanently embedded within the solid coalized pure metallic mass of the tool body, and each abrasive granule is intimately enclosed at all sides only by pure metal. Hence, each abrasive granule remains intact as originally supplied, and of full dimensions and in structurally unweakened form whereby the grip of the metallic matrix upon the abrasive granule is of maximum strength and durability.

Thus, the invention clearly distinguishes from and provides marked improvements and advantages over prior methods for mounting abrasive granules within metallic holders. For example, in order to avoid the well known disadvantages and structural weaknesses of sintered tool bodies, a previously customary method for mounting abrasive granules involves minute cutting into the outer surfaces of a metallic body and inlaying abrasive granules into the cuts so produced, as by pounding or otherwise driving the abrasive therein. Obviously, such methods result in tremendous reduction of abrasive grain size and pulverizing thereof so that the granules become so fractured that the enclosing metal portions cannot cling solidly to the abrasive; whereas the tool of the present invention entirely avoids such destruction of the abrasive granules and encases each grain with a solid pure metal grip of maximum tenacity.

As illustrated in Figs. 5 and 6, another form of wheel 19 of the invention is shown as comprising a metallic core 20 around about the periphery of which has been wound a metallic strip 22 to provide a plurality of layers, the number of which depends upon the desired depth of the working portion of the wheel. The abrasive granules 24 for the wheel are positioned upon the metallic strip 22 prior to the wrapping of the strip about the core 20 by spreading a supply of the loose granules across the strip 22, and it will be understood that Fig. 4 also illustrates the mounting of the abrasive granules 24 upon the base metal elements 22 of the invention.

Upon completion of the process of winding the strip about the core 10, the wheel 19 is placed in a furnace and/or otherwise subjected to an elevated temperature at about the degree of initial fusion of the metal of the strip 22 for a length of time sufficient to provide thorough welding of adjacent portions of the grit-carry-strip without allowing the bulk of the metal thereof to become so fluid as to allow the impounded abrasive particles to move relative to the mass. Usually, an application of pressure upon the structure during the heating process will also be beneficial and of assistance in providing a thorough welding.

Whenever the stock to be operated upon by the wheel is not initially shaped complementary to the shape of the wheel cutting face, that section of the wheel that is called upon to do the majority of the work will preferably be provided with an increased concentration of abrasive kernels as compared to the other portions of the wheel. To obtain such an arrangement of abrasive kernel concentration, the strip 22 may be provided, as illustrated in Fig. 7, with an increased number of grits per unit of area in the central portion of the strip as compared to the side edge portions thereof. Hence, when the strip 22 is wound about the core 20 and fused into place thereon, the central section of the

wheel will be richer in abrasive grit as compared to the side portions thereof. Consequently, the abrasive grit is employed in accurately controllable manner, and wasteful employment of abrasive kernels in the relatively inactive portions of the wheel is avoided thus effecting substantial economies whenever the abrasive kernels are of the expensive type such as diamond dust or the like. Also, it will be seen that because of the fact that the relatively inactive portions of the wheel are of reduced abrasive character, the process of redressing the wheel after the design of the cutting face has been deformed will be less difficult and will involve less loss of valuable abrasive material.

It will be understood that the desired kind of abrasive distribution throughout the wheel section may be obtained in ways other than hereinabove described in connection with preparation of the strip 22. For example, a strip of uniform character may be employed and the abrasive grits may be applied thereto in any suitable manner so as to give the desired form of grain distribution. For example, the coating of abrasive carrying substance 18 which is applied to the strip preparatory to winding thereof about the core may be applied of increased thickness along the center line of the strip; or, the strip may be painted by multiple operations involving the application of a mixture along the center line of the strip that contains a higher percentage of abrasive to the carrier employed as compared to the percentage of abrasive to the carrier employed in connection with the painting of the side edge portions of the strip.

In any case it will be seen that the object is to locate the abrasive kernels in accord with a predetermined desired manner of distribution throughout the wheel body by temporarily impounding the abrasive kernels in the component elements entering into the assembly of the abrasive wheel and subsequently fusing the elements thereof together into a unitary mass of high structural strength without substantially disturbing the distribution and relative concentration of the abrasive kernels throughout different portions of the wheel mass.

Thus, the method of the invention provides a rugged welded structure wherein the matrix portion thereof is of pure coalized metal form. This provides a tool of greater structural strength as compared to the so-called "sintered" wheels of the prior art, for example, which are made by fusing granular metallic mixtures. In the case of such sintered types of tools the finished products are of crystalline-like structural form and resemble in appearance crusty masses of granules adhering to one another by reason only of intermittent and spaced points of welded contact, and the masses are usually interspersed with multitudes of minor voids. Thus, the abrasive grains are at best only partially surrounded by and attached to the bonding material. Consequently, the finished products of such prior methods are usually non-uniform as to structural strength and often contain weak zones which are apt to cause unduly rapid wearing and/or disruption of the mass when used under heavy duty or high speed conditions. As distinguished from such prior types of abrasive material structures, the laminar body elements of the invention, upon being fused together into an integral mass, provide a tool that is made up of a plurality of

united solid metallic bodies extending throughout the tool structure; and therefore, even though the fusion process of the method of the present invention may not in some instances be carried out to perfection between all of the adjacent surface portions thereof, the tool will nevertheless be reinforced throughout by the unaltered integral solid metallic bodies. Thus, in no case will the tool of the invention be subject to disruption under stress in the manner of sintered wheels, or the like. In the case of production of tools of the present invention in the form of abrasive wheels as illustrated in the drawing, it will be seen that the laminated strip structures 11-22, upon being welded together provide tools that are positively reinforced circumferentially against centrifugal and/or other forces tending to disrupt them during use.

The avoidance of conditions of fluidity in the metal of the structure during the fusion process precludes the possibility of redistribution of the abrasive grains in the mass and/or undesirable segregation thereof as would otherwise occur under conditions of mass metal fluidity; and the planned unequal distribution of abrasive particles throughout the wheel mass is accordingly obtained in the finished product. It is of course contemplated that the strip elements 11-22 may be bent or dished or otherwise deformed in any desired manner before being relatively assembled so as to provide any desired form of interlocking laminated structure.

It will be understood that the invention is applicable with equal facility to the manufacture of a large variety of abrasive tool shapes such as are suitable for use in connection with a multiplicity of industries, and that although only a limited number of the forms of the invention have been shown and described in detail herein, various changes may be made therein without departing from the spirit of the invention or the scope of the appended claims.

I claim:

1. The method of fabricating an abrasive tool including the steps of arranging abrasive granules between metallic sheet material while holding said abrasive granules in position therebetween in accord with a plan of irregular distribution to provide a fabrication assembly, heating said metallic material to soften the latter so that said abrasive granules may press into said metallic material without becoming subjected to granule-crushing pressures, pressing said assembly together while heated to metallic softened condition and heat-fusing and pressing the assembled metallic material and abrasive granules together to form a coalized body of metal with abrasive granules of unchanged form dispersed therethrough and intimately locked therein in accord with said plan of abrasive granule distribution.

2. The method of fabricating an abrasive tool including the steps of applying lauryl alcohol to surface portions of metallic sheet material and arranging abrasive granules upon said lauryl alcohol treated portions of said metallic sheet material for holding said abrasive granules in position therebetween in accord with a plan of irregular distribution, and heat-fusing and pressing the assembled metallic material and abrasive granules together with pressure forces regulated so as to avoid crushing of said granules to form a coalized body of metal with abrasive granules of unchanged form dispersed therethrough and

intimately locked therein in accord with said plan of abrasive granule distribution.

3. The method of manufacturing an abrasive tool including the steps of applying an adhesive substance to surface portions of metallic material, mounting abrasive granules upon said applied adhesive substance in accord with a definite plan of abrasive granule distribution, arranging said metallic material to provide a laminated structure, heating said metallic material to soften the latter so that said abrasive granules may press thereinto without becoming subjected to granule-crushing pressures, pressing said laminated structure together while heated to metallic material softened condition, and sintering said structure into a unitary metallic body with said abrasive granules locked by sintered metal therein in accord with said definite plan of abrasive granule distribution, said adhesive substance being of such character as to be eliminated upon sintering of said structure.

4. The method of manufacturing an abrasive tool including the steps of providing in association with surface portions of metallic discs means for temporarily pocketing in fixed relation thereon abrasive granules in accord with a definite plan of abrasive granule unequal distribution whereby the concentration of said granules varies with respect to different of said discs, arranging said discs into the form of a single laminated structure with said abrasive granules temporarily supported by said pocketing means therewithin, heating said metallic material to soften the latter so that said abrasive granules may press thereinto without becoming subjected to granule-crushing pressures, pressing said laminated structure together while heated to metallic material softened condition, and fusing the metallic portions of said laminated structure together so as to provide a unitary body with said abrasive granules locked by said fused metallic portions therewithin in accord with said definite plan of abrasive granule distribution, said granule temporary pocketing means being of such character as to be eliminated upon fusing of said structure.

5. The method of manufacturing an abrasive wheel tool comprising the steps of applying adhesive substance to a surface portion of a metallic strip element, pocketing abrasive granules in fixed relation upon said adhesive substance, said abrasive granules being distributed in accord with a definite plan of abrasive granule unequal distribution whereby the concentration of said granules is greater on one sectional zone of said strip element than on another sectional zone thereof, coiling said strip element to provide a wheel structure, heating said metallic material to soften the latter so that said abrasive granules may press thereinto without becoming subjected to granule-crushing pressures, pressing said laminated structure together while heated to metallic material softened condition, and fusing said wheel structure into a unitary metallic body with said abrasive granules locked by fused metal therein in accord with said definite plan of abrasive granule distribution, said adhesive substance being of such character as to be volatilized and dissipated upon fusing of said structure.

6. The method of manufacturing an abrasive tool comprising the providing in association with surface portions of metallic discs means for temporarily pocketing in fixed relation thereon abrasive granules in accord with a definite plan

of abrasive granule unequal distribution whereby the concentration of said granules varies with respect to different of said discs, arranging said discs into the form of a single laminated structure with said abrasive granules temporarily supported by said means therewithin, heating said metallic material to soften the latter so that said abrasive granules may press therewithout becoming subjected to granule-crushing pressures, pressing said laminated structure together while heated to metallic material softened condition, and fusing the metallic portions of said laminated structure together so as to provide a unitary body with said abrasive granules locked by said fused metallic portions therewithin in accord with said definite plan of abrasive granule distribution, said granule temporary pocketing means being of such character as to be volatilized and dissipated upon fusing of said structure.

7. The method of manufacturing an abrasive tool comprising the steps of arranging in association with a surface portion of a copper-aluminum alloy metallic strip element means for temporarily pocketing in fixed relation upon said strip element abrasive granules in accord with a definite plan of abrasive granule unequal distribution whereby the concentration of said granules is greater in one sectional zone of said strip element than in another sectional zone thereof, said granule temporary pocketing means being of such character as to be eliminated under elevated temperature conditions, arranging said abrasive mounting strip to provide a laminated structure, and fusing said structure into a unitary metallic body with said abrasive granules locked by fused metal therein in accord with said definite plan of abrasive granule distribution, and subsequently tempering the metallic structure of the tool by heating and quenching processes.

8. The method of manufacturing an abrasive tool comprising the steps of providing in association with surface portions of copper-aluminum alloy metallic laminae means for temporarily pocketing in fixed relation thereon abrasive granules in accord with a definite plan of abrasive granule unequal distribution whereby the concentration of said granules varies with respect to different of said laminae, said granule temporary pocketing means being of such character as to be eliminated upon fusing of said metallic laminae, arranging said laminae into the form of a single laminated structure with said abrasive granules temporarily supported by said means therewithin, and fusing the metallic portions of said laminated structure together so as to provide a unitary body with said abrasive granules locked by fused metal therein in accord with said definite plan of abrasive granule distribution, and subsequently tempering the metallic portion of said tool by heating and quenching processes.

9. An abrasive tool comprising copper-aluminum alloy laminae having abrasive granules pocketed thereon in accord with a definite plan of unequal distribution, said laminae being fused to provide a coalized body, said body having been heat treated for tempering of the metallic alloy content thereof.

10. The method of manufacturing an abrasive tool comprising the steps of arranging in association with a surface portion of a steel metallic strip element means for temporarily pocketing in fixed relation upon said strip element abrasive granules in accord with a definite plan of abrasive

granule unequal distribution whereby the concentration of said granules is greater in one sectional zone of said strip element than in another sectional zone thereof, said granule temporary pocketing means being of such character as to be eliminated under elevated temperature conditions, arranging said abrasive mounting strip to provide a laminated structure, and fusing said structure into a unitary metallic body with said abrasive granules locked by fused metal therein in accord with said definite plan of abrasive granule distribution, and subsequently tempering the metallic structure of the tool by heating and quenching processes.

11. The method of manufacturing an abrasive tool comprising the steps of providing in association with surface portions of steel laminae means for temporarily pocketing in fixed relation thereon abrasive granules in accord with a definite plan of abrasive granule unequal distribution whereby the concentration of said granules varies with respect to different of said laminae, said granule temporary pocketing means being of such character as to be eliminated upon fusing of said metallic laminae, arranging said laminae into the form of a single laminated structure with said abrasive granules temporarily supported by said means therewithin, and fusing the metallic portions of said laminated structure together so as to provide a unitary body with said abrasive granules locked by said fused metallic portions therewithin in accord with said definite plan of abrasive granule distribution, and subsequently tempering the metallic portion of said tool by heating and quenching processes.

12. The method of manufacturing an abrasive tool comprising the steps of arranging in association with a surface portion of a heat temperable strip element means for temporarily pocketing in fixed relation upon said strip element abrasive granules in accord with a definite plan of abrasive granule unequal distribution whereby the concentration of said granules is greater in one sectional zone of said strip element than in another sectional zone thereof, said granule temporary pocketing means being of such character as to be eliminated under elevated temperature conditions, arranging said abrasive mounting strip to provide a laminated structure, and fusing said structure into a unitary metallic body with said abrasive granules locked by fused metal therein in accord with said definite plan of abrasive granule distribution, and subsequently tempering the metallic structure of the tool by heating and quenching processes.

13. The method of manufacturing an abrasive tool comprising the steps of providing in association with surface portions of temperable laminae means for temporarily pocketing in fixed relation thereon abrasive granules in accord with a definite plan of abrasive granule unequal distribution whereby the concentration of said granules varies with respect to different of said laminae, said granule temporary pocketing means being of such character as to be eliminated upon fusing of said metallic laminae, arranging said laminae into the form of a single laminated structure with said abrasive granules temporarily supported by said means therewithin, and fusing the metallic portions of said laminated structure together so as to provide a unitary body with said abrasive granules locked by said fused metallic portions therewithin in accord with said definite plan of abrasive granule distribution, and subse-

quently tempering the metallic portion of said tool by heating and quenching processes.

14. An abrasive tool comprising steel laminae having abrasive granules pocketed thereon in accord with a definite plan of unequal distribution, said laminae being fused to provide a coalized body, said body having been heat treated for tempering of the metallic content thereof.

15. An abrasive tool comprising temperable metallic laminae having abrasive granules pocketed thereon in accord with a definite plan of unequal distribution, said laminae being fused to provide a coalized body, said body having been heat treated for tempering of the metallic content thereof.

16. The method of manufacturing an abrasive tool comprising acid etching surface portions of metallic laminae to provide pocket means, temporarily pocketing in fixed relation thereon abrasive granules in accord with a definite plan of abrasive granule distribution whereby the concentration of said granules varies with respect to different of said laminae, arranging said laminae into the form of a single laminated structure with said abrasive granules temporarily supported by said pocketing means therewithin, and sintering the metallic portions of said laminated structure together so as to provide a unitary body with said abrasive granules locked by said sintered metallic portions therewithin in accord with said definite plan of abrasive granule distribution.

17. The method of manufacturing an abrasive

5 tool comprising applying to surface portions of metallic laminae lauryl alcohol, temporarily pocketing in fixed relation thereon abrasive granules in accord with a definite plan of abrasive granule distribution whereby the concentration of said granules varies with respect to different of said laminae, arranging said laminae into the form of a single laminated structure with said abrasive granules temporarily supported by said lauryl alcohol therewithin, and sintering the metallic portions of said laminated structure together so as to provide a unitary body with said abrasive granules locked by said sintered metallic portions therewithin in accord with said definite plan of abrasive granule distribution.
